MACHINE FOR CORKING BOTTLES

Robert Arthur Clark, Jr., Owensboro, Ky., assignor to Glenmore Distilleries Company, Inc., Owensboro, Ky.

Application August 19, 1942, Serial No. 455,377

6 Claims. (Cl. 226—92)

My invention relates to improvements in bottle corking machines for inserting flanged type corks in beverage bottles.

The invention is designed with the particular objects in view of providing a practical, high-speed machine for inserting such corks automatically in a continuously fed stream of bottles and which is adapted for adjustment to compensate in operation for various tolerances occurring in the manufacture of bottles, whereby breakage of the bottles, by crushing, is obviated and which is, furthermore, simple in construction, operative from a single low-power source, requires a minimum of servicing, and is comparatively inexpensive to manufacture and install.

Other and subordinate objects are also comprehended by my invention, all of which, together with the precise nature of my improvements, will be readily understood when the succeeding description and claims are read with reference to the drawings accompanying and forming part of this specification.

In said drawings:

Figure 1 is a fragmentary view in front elevation illustrating my improved machine in its preferred embodiment.

Figure 2 is a view in horizontal section taken on the line 2—2 of Figure 1 and drawn to an enlarged scale.

Figure 3 is a view in vertical section taken on the line 3—3 of Figure 1 and also drawn to an enlarged scale.

Figure 4 is a view in horizontal section taken on the line 4—4 of Figure 3.

Figure 5 is a view in transverse section taken on the line 5—5 of Figure 4 and drawn to an enlarged scale.

Figure 6 is a view in horizontal section taken on the line 6—6 of Figure 1 and drawn to an enlarged scale.

Figure 7 is a fragmentary view in front elevation of the bottom plate of the cork carrying head, one pair of the cork-gripping fingers, and stops therefor.

Figure 8 is a view in perspective of one of the cork-gripping fingers.

Figure 9 is a fragmentary view in vertical longitudinal section of the cork-feeding chute, the cork ejector means, and the ejector control means.

Figure 10 is a fragmentary view in longitudinal section taken on a line 10—10 of Figure 9.

Figure 11 is a similar view taken on a line 11—11 of Figure 9, and

Figure 12 is a view in longitudinal section of the ejector control valve and parts associated therewith.

Referring to the drawings by numerals, 1 designates the base of the machine having a top bedplate 2, and which is of any suitable height and

elongated form, the particular construction thereof, with the exception of the parts herein-after specifically referred to, being immaterial to the invention. Rising from the back of the base 1 is a suitable pedestal 3 supporting at its upper end a vertically disposed, substantially cylindrical, open bottom housing 4 overhanging the bed plate 2 and for a purpose presently seen.

A vertically disposed drive shaft 5 extends upwardly through the base 1 and the bedplate 2 and into the housing 4. The drive shaft may be journaled in any suitable manner at its lower end in the base 1 and extends intermediate its ends through a bearing collar 6 and a horizontal partition plate 7 provided in the base 1 below the bedplate 2. The drive shaft 5 is designed to be driven, clockwise as seen in Figure 2, by a suitable motor drive housed in the base 1 below the plate 7, but, such drives being well known, it has not been deemed necessary to illustrate the same.

At the top of the drive shaft 5 and projecting slightly out of the bottom of the housing 4, for a purpose presently seen, is a cork carrying head 8 of cylindrical drum-like form having top and bottom plates 9, 10, fixed therein, and an axial sleeve 11 extending therethrough and below the same over the drive shaft 5 to which it is suitably fixed for rotation of said head by said shaft. A circular series of vertically disposed cylinders 12 are fixed at their ends in the plates 9, 10 of the head 8 in 90° angular relation, with screw plugs 13 in the upper ends thereof. Each cylinder 12 contains in its lower end a piston 14 having a stem 15 vertically slidable in the plug 13, the piston being urged downwardly by a coil spring 16 surrounding the stem 15 between the plug and the piston. The plugs 13, as will be clear, provide for variably tensioning the springs 16 to correspondingly tension the pistons 14 against vertical movement. Pairs of cork-gripping fingers 17 are provided on the bottom plate 10 of said head 8 to underlie the pistons 14 flat against the same, each pair of fingers being pivoted at inner ends thereof, as at 18, to the plate 10 to extend

40 in laterally spaced relation across the pistons 14 upon diametrically opposite sides thereof and toward the periphery of the head 8. Studs 19 depends from the pistons 14 in between the axis of said pistons and the pivots 18 maintain the fingers 17 of said pairs substantially parallel in each pair and in opposition to coil springs 20 suitably connected to said fingers 17 as best shown in Figure 6.

At this point, it may be explained, that the 55 pairs of cork-gripping fingers 17 are designed to frictionally grip between the opposed sides thereof of corks 21 and by means of the flanges 22 thereof, with said flanges imposed flat against the bottoms of the pistons 14 and centered relative to 60 said pistons by the studs 19 as shown, for in-

stance, in Figure 3, and further that said fingers in the pairs are designed to be separated in opposition to the springs 20 to release the corks 21 and by upward thrusts of the mouths of bottles, not shown, between the fingers of the pairs. To facilitate such separation of the pairs of fingers 17, the inner sides thereof are beveled, as at 23, along the lower corners thereof. To facilitate entering corks 21 between the pairs of fingers 17 their outer ends are rounded as at 24. As will, of course, be understood, the fingers 17 are appropriately spaced apart in each pair normally to hold the corks 21 and for camming apart by the mouths of the bottles.

Directly in front of the head 8 is a gravity feed cork chute 25 of inverted channel form for receiving the heads 22 of the corks 21 therein, said chute curving downwardly and rearwardly to the head 8 and provided with spaced-apart, track-forming, side edge flanges 26 terminating under the plate 10 outwardly of the path of revolution of the pairs of fingers 17, the arrangement being such that the pairs of fingers 17 align with the lower discharge end of said chute 25 as said fingers are revolved past said chute. The chute 25 is designed to be supplied at its upper end with corks 21 from a suitable hopper, as at 25', and so that said chute is always full of corks 21 depending from the chute and for gravity feed thereof toward the discharge end of the chute.

Pneumatic means are provided for ejecting the corks 21 from the chute 25 successively by blowing the same in between the pairs of fingers 17 as the latter are revolved past the discharge end of said chute 25. Such means comprises a pneumatic valve cylinder 27 surmounting the chute 25 with an open end opposed to the housing 4, said cylinder being mounted on said chute by means of a bracket 28. A compressed air line 29 leading from a suitable source of air under pressure, not shown, extends into the top of the cylinder 27 centrally thereof, and a pair of air feed lines 30 extend from opposite sides of the cylinder 27 in its transverse center to a pair of air ejecting jets 31 suitably extended through opposite sides of the chute 25 adjacent to the discharge end of said chute. A valve unit is slidably mounted in the cylinder 27 comprising a plunger 32 extending out of the open end of the cylinder, an axial piston rod 33 extending from one end of the plunger and endwise slidable in the other end of said cylinder, a piston-type valve 34 fixed on said rod for opening and closing the lines 29, 30, a coil spring 35 on said rod interposed between the valve 34 and said other end of the cylinder 27, and a button 36 extending from the plunger 32 toward said housing 4 and close thereto. The spring 35 urges the valve 34 and plunger outwardly of the cylinder 27 toward the housing 4. A stop collar 37 on the rod 33 abutting the adjacent cylinder end establishes the normal position of the unit in which the valve 34 closes said lines 29, 30. Suitable tappets 28 on the periphery of the head 8 vertically aligned with the pairs of fingers 17 are provided to wipe against the button 36 under revolution of the head 8 and to thereby move the described valve unit inwardly of the cylinder 27 in opposition to the spring 35 so as to uncover or open the lines 29, 30 momentarily.

A cork ejector control means is provided and which will now be described. Extending laterally from one side of the chute 25 closely adjacent to the discharge end thereof is a pneumatic cylinder 39 clamped to said side by clamping nuts

40, see Fig. 11, and having a threaded bushing 41 in its inner end. Slidably extended out of said cylinder 39 is an ejector control rod 42 having an angular inner stop end 43 adapted to project in front of the leading cork 21 in the chute 25 and thereby prevent the corks from being ejected out of said chute. A coil spring 44 surrounding the rod between the bushing 41 and a piston 45 on said rod normally retracts said rod inwardly of said cylinder 39 to retract the stop ends 43 out of the path of feed of the corks 21. The stop ends 43 engaging the bushing 41 limit retraction of the ejector rod 42. A compressed air line 46 coupled to the outer end of the cylinder 39, as at 47, extends to a port 48 in one side of a pneumatic ejector control cylinder 49 suitably mounted in horizontally extending position on a fixed part 50 on the bed plate 2 adjacent the front edge thereof and directly in front of the drive shaft 5. A compressed air supply line 51 extends from the before-mentioned source (not shown) into one end of said cylinder 49. Slidably extended outwardly of the other end of said cylinder 49 is a valve operating piston rod 51 having fast on its inner end a piston-like valve 52 normally uncovering the port 48 and adapted for advance through the medium of the rod 51 to cover said port. Longitudinal grooves 52' in the cylinder 49 provide for air from the supply line 51 passing from one side of the piston to the other and to the port 48. For advancing the piston 52, an ejector control lever 53 extends horizontally rearwardly over the bedplate 2 in front of the drive shaft 5 for rocking movement about an upstanding post 54 on said plate 2, said lever being elevated above the bedplate 2 and having an oppositely extending, bifurcated, tail piece 55 on the opposite side of the pivot straddling the rod 51 between a pair of collars 56 on said rod, the arrangement being such that movement of said lever 53 from a normal position will advance the valve 52 to close the port 48. A coil spring 57, suitably connected to a stud 58 on said rod 51 and to the fixed part 50 yieldingly holds the valve 52 in normal uncovering position, and the lever 53 in normal position established by engagement of its tail piece 55 with a fixed stop 59 rising from the bedplate 2.

As will now be seen, the air from the source is normally admitted to the cylinder 49 and to the cylinder 39 so that the ejector rod 42 is normally projected in opposition to the spring 44 and the stop end 43 of said rod is interposed in front of the foremost cork 21 to prevent corks from being ejected out of the chute 26.

For thrusting bottles upwardly against the corks 21, an annular turntable 60 is suitable fixed to the drive shaft 5 and set into the bedplate 2 flush therewith. The turntable 60 rests on a set collar 61 fastened on said drive shaft 5. A circular series of cylindrical, bottle supporting and elevating plungers 62 are provided in the turntable 60 in 90 degree angular relation and in vertical alignment with the pistons 14, which is to say also with the pairs of fingers 17. The plungers 62 are vertically slidable axially in bushings 63, 16 and depending from the turntable 60. Set screws 64 in the bushings 63 and extending into the keyways 65 in the plungers 62 hold the latter against rotation in the bushings. The plungers 62 are hollow for lightness and have bottom cap plates 66 bolted thereto as at 67. The bottle elevating and supporting plungers 62 are moved from a normal position in which their upper ends 75 are flush with the turntable 60, first upwardly

from and then downwardly to normal position under revolution of the turntable 60 and through substantially 180 degrees of movement clockwise as viewed in Figure 2, the upward movement starting substantially at 90 degrees of revolution of each plunger from the starting point in which the pair of fingers 17 aligned with the plunger are opposite to the discharge end of the chute 25.

The means for elevating and lowering said plungers 62 comprises a track forming, arcuate cam 68 suitably fixed on the partition plate 1 concentrically of the drive shaft 5. Beneath each plunger 62 in the center thereof, is a roller jacking unit comprising a pair of upstanding, laterally spaced, links 69 having a pair of upper and lower rollers 70, 71 rotatably mounted between the upper and lower ends thereof, the upper roller supporting the plungers 62 and the lower adapted to ride up and down the cam 68 and on the plate 1. Each pair of links 69 is suitably fixed to one end of an arm 72 pivoted at its other end, as at 73, to the bottom of the turntable 60 for vertical swinging movement.

Vertically movable with each plunger 62 is a bottle aligning yoke 74 horizontally disposed to straddle the neck of a bottle located on the plunger and fixed by a collar 75 on a vertical rod 76 vertically slideable through the turntable 60 alongside the bushing 63 and mounted on the bottom of the cap plate 66 by a spider 77 bolted, as at 78, to said cap plate and to which the rod 76 is fixed by nuts 79. Collars 75 slide in vertical grooves 80 provided in the before-mentioned sleeve 11 to steady the yokes 74.

Mechanism for feeding bottles into the machine in a stream is provided as follows:

A slat type, traveling conveyor 81 is set into the bed plate 2 in front of the turntable 60 to extend lengthwise longitudinally of the base 1 and to be driven from left to right as viewed in Figures 1 and 2.

A pair of feeding units 82, 83 are provided at opposite sides of the turntable 60 for feeding bottles laterally from the conveyor 81 onto the turntable 60 and similarly feeding the bottles off said turntable back onto said conveyor 81, the unit 82 being arranged forwardly of said turntable and the unit 83 rearwardly thereof as regards the direction of travel of the conveyor 81. Each unit 82, 83 comprises a pair of upper and lower spaced apart disks 84, 85 fixed on a central hub 86 fast on the upper end of a vertical shaft 87 above the bed plate 2, said disks overlying the conveyor 81 at their front edges and also overlying the turntable 60. The disks 84, 85 are provided with vertically aligned pairs of edge notches 88 arranged in 90 degree angular relation and which are adapted, in the case of the unit 82 to move bottle laterally and rearwardly off the conveyor 81 over the turntable 60 onto the plungers 62 just before the latter begin to ride, and in the case of the unit 83 to similarly move bottles off the plungers 62 back onto the conveyor 81 as soon as said plungers descend level with the turntable 60.

Shafts 87 of the units 82, 83 are operated to revolve the units in the same direction, i. e., counterclockwise as viewed in Figure 2, and at the same speed, by means of a sprocket and chain drive 89 between the drive shaft 5 and said shafts 87 as represented in dotted lines in Figure 1.

Preferably the conveyor 81 is driven from one shaft 87 on a bevel gear drive represented in dotted lines at 90 in Figure 1. The described injector control lever 53 is disposed over the conveyor 81 to extend between the disks 84, 85 of

the unit 82 for operation by each bottle as it is moved off the conveyor 81 onto the turntable 60 and plungers 62.

The before described head 8 may be provided on 5 the plate 10 thereof with a circular series of stops 91 for limiting separated movement of the pairs of cork gripping fingers 17.

A suitable slot 92 is provided in the front of the housing 4 to provide for engagement of the tappets 38 with the buttons 36.

Referring now briefly to the operation, bottles are moved in succession from the conveyor 81, in the manner already described, on to the turntable 60 and plungers 62. As each bottle is so 15 moved it wipes against the ejector control lever 53. The lever 53 retracts valve 52 to cover and close the port 48, thereby shutting off compression in the air line 46 and pneumatic cylinder 39 with the result that the spring 44 momentarily 20 retracts the stop end 43 of the ejector control rod 42, from in front of the leading cork 21 in the chute 25. The first tappet 38 to engage the button 36 of the valve unit of the pneumatic valve, under rotation of the head 8, operates said unit 25 in opposition to the spring 35 to momentarily open the lines 29, 30 with the result that air under pressure is discharged through the jets 31 to blow the leading cork out of the chute 25 in 30 between the appropriate pair of cork gripping fingers 17 for corking the bottle being moved from the conveyor 81 on to the plunger 62 vertically aligned with the pair of cork gripping fingers 17. The plunger 62 is next raised by the cam 68 and described roller jacking unit, thereby elevating 35 the neck of a bottle to insert the cork therein, while, at the same time, as the cork is forced home, the mouth of the bottle extends between the pair of fingers 17 and by coaction with the bevel edges 23 thereof cams the same apart thus 40 releasing the cork. As will be seen, the cork is forced home in the mouth of the bottle against the appropriate piston 14 which yieldingly opposes the cork. The plunger 62 now descends with the corked bottle and the latter is removed 45 from the supporting plunger 62 and the turntable 60 back onto the conveyor 81 for passage out of the machine. The described operations are repeated with each bottle. As will be seen, by varying 50 the tension on the piston 14 in the manner already described, the corks may be forced home without splitting the mouth of the bottle, the pistons yielding to compensate for variations in sizes of the mouths of the bottles as will be clear.

Guard rails 93 fixed to the bed plate 2 by uprights 94 and over the conveyor 81 curve from said conveyor over the turntable 60 to guide the bottles off of and onto said conveyor.

The foregoing will, it is believed, suffice to impart a clear understanding of my invention without further explanation.

Manifestly the invention, as described, is susceptible of modification without departing from the inventive concept, and right is herein reserved to such modifications as fall within the scope of the subjoined claims.

I claim:

1. In a machine for inserting flanged top corks in bottles, a base, a cork carrying head above said base rotating about a vertical axis, a gravity feed chute for holding a line of corks heads uppermost and having a discharge end underlying the bottom of said head, a plurality of pairs of cork holding fingers arranged in a circular series on the bottom of said head for rotation 70 past said end of the chute by said head to re-

leasably grip corks discharged from said end therebetween, rotary means for supporting bottles upright and vertically aligned with said pairs of fingers and operative under rotation thereof to elevate said bottles for inserting the finger held corks in the mouths thereof, said means subsequently lowering said bottles, means to feed bottles in succession onto said rotary means in upright position, and pneumatic means for ejecting the corks in said line successively out of the discharge end of the chute in between said pairs of fingers and including an air jet operative intermittently under control of said head in timed relation to rotation of said pairs past said end of the chute.

2. In a machine for inserting flanged top corks in bottles, a base, a cork carrying head above said base rotating about a vertical axis, a gravity feed chute for holding a line of corks heads uppermost and having a discharge end underlying the bottom of said head, a plurality of pairs of cork holding fingers arranged in a circular series on the bottom of said head for rotating past said end of the chute by said head to releasably grip corks discharged from said end therebetween, rotary means for supporting bottles upright and vertically aligned with said pairs of fingers and operative under rotation thereof to elevate said bottles for inserting the finger held corks in the mouths thereof, said means subsequently lowering said bottles, means to feed bottles in succession onto said rotary means in upright position, and pneumatic means for ejecting the corks in said line successively out of the discharge end of the chute in between said pairs of fingers in timed relation to rotation of said pairs past said end of the chute, said feeding means comprising a conveyor on said base traveling past said rotary means at one side thereof, and for supporting a line of bottles, and rotary devices for moving successive bottles in said line laterally off said conveyor onto said rotary means, and pneumatic means to control ejection of the corks out of said chute operative by movement of the bottles off said conveyor.

3. In a machine for inserting flanged top corks in bottles, a base, a cork carrying head above said base rotating about a vertical axis, a gravity feed chute for holding a line of corks heads uppermost and having a discharge end underlying the bottom of said head, a plurality of pairs of cork holding fingers arranged in a circular series on the bottom of said head for rotation past said end of the chute by said head to releasably grip corks discharged from said end therebetween, rotary means for supporting bottles upright and vertically aligned with said pairs of fingers and operative under rotation thereof to elevate said bottles for inserting the finger held corks in the mouths thereof, said means subsequently lowering said bottles, means to feed bottles in succession onto said rotary means in upright position, and pneumatic means for ejecting the corks in said line successively out of the discharge end of the chute in between said pairs of fingers in timed relation to rotation of said pairs past said end of the chute, and controlled conjointly by rotation of said head and movement of bottles onto the rotary means.

4. In a machine for inserting flanged top corks in bottles, a base, a cork carrying head above said base rotating about a vertical axis, a gravity feed chute for holding a line of corks heads up-

permost and having a discharge end underlying the bottom of said head, a plurality of pairs of cork holding fingers arranged in a circular series on the bottom of said head for rotation past said end of the chute by said head to releasably grip corks discharged from said end therebetween, rotary means for supporting bottles upright and vertically aligned with said pairs of fingers and operative under rotation thereof to elevate said bottles for inserting the finger held corks in the mouths thereof, said means subsequently lowering said bottles, means to feed bottles in succession onto said rotary means in upright position, and pneumatic means for ejecting the corks in said line successively out of the discharge end of the chute in between said pairs of fingers in timed relation to rotation of said pairs past said end of the chute, said pneumatic means including air blast devices in said chute, and means to introduce air under pressure to said devices controlled by rotation of said head.

5. In a machine for inserting flanged top corks in bottles, a base, a cork carrying head above said base rotating about a vertical axis, a gravity feed chute for holding a line of corks heads uppermost and having a discharge end underlying the bottom of said head, a plurality of pairs of cork holding fingers arranged in a circular series on the bottom of said head for rotation past said end of the chute by said head to releasably grip corks discharged from said end therebetween, rotary means for supporting bottles upright and vertically aligned with said pairs of fingers and operative under rotation thereof to elevate said bottles for inserting the finger held corks in the mouths thereof, said means subsequently lowering said bottles, means to feed bottles in succession onto said rotary means in upright position, and pneumatic means for ejecting the corks in said line successively out of the discharge end of the chute in between said pairs of fingers in timed relation to rotation of said pairs past said end of the chute, said pneumatic means comprising cork releasing means on said chute normally blocking ejection of the corks from the chute.

6. In a machine for inserting flanged top corks in bottles, a base, a cork carrying head above said base rotating about a vertical axis, a gravity feed chute for holding a line of corks heads uppermost and having a discharge end underlying the bottom of said head, a plurality of pairs of cork holding fingers arranged in a circular series on the bottom of said head for rotation past said end of the chute by said head to releasably grip corks discharged from said end therebetween, rotary means for supporting bottles upright and vertically aligned with said pairs of fingers and operative under rotation thereof, to elevate said bottles for inserting the finger held corks in the mouths thereof, said means subsequently lowering said bottles, means to feed bottles in succession onto said rotary means in upright position, and pneumatic means for effecting the corks in said line successively out of the discharge end of the chute in between said pairs of fingers in timed relation to rotation of said pairs past said end of the chute, said pneumatic means comprising cork releasing means on said chute normally blocking ejection of the corks from the chute, and operative to ineffective position as an incident to feed of each bottle onto said rotary means.

ROBERT ARTHUR CLARK, JR.
